Primary Examiner—Doris V. Coles
Attorney, Agent, or Firm—Terry M. Gernstein[57] **CLAIM**

The ornamental design for a combined fish and fishing accessory container, as shown and described.

DESCRIPTION

FIG. 1 is a top, front and end perspective view of the combined fish and fishing accessory container showing my new design;

FIG. 2 is a front elevational view thereof;

FIG. 3 is a rear elevational view thereof;

FIG. 4 is an end elevational view thereof, the end opposite being a mirror image of the end shown in FIG. 4;

FIG. 5 is a top plan view thereof; and,

FIG. 6 is a bottom plan view thereof.
